UNITED STATES PATENT OFFICE.

JOHN QUINCY REED, OF NEW YORK, N. Y., ASSIGNOR TO THE BUTTERICK PUBLISHING CO., (LIMITED,) OF SAME PLACE.

DESIGN FOR A LADY'S POLONAISE.

SPECIFICATION forming part of Design No. 14,433, dated November 20, 1883.

Application filed August 23, 1883. Term of patent 3½ years.

To all whom it may concern:

Be it known that I, JOHN QUINCY REED, of the city, county, and State of New York, have invented and produced a new and original 5 Design for a Pattern of a Lady's Polonaise, (numbered 8,841;) and I do hereby declare that the engraved prints accompanying this specification convey to any one accustomed to using paper patterns a clear understanding of how 10 a garment made up by the pattern will appear.

The design combines closely-fitted fronts, buttoned for part of their length, and draped to fall in deep points by plaits in their back

edges, and a closely-fitted back that falls deep and square, and is draped in plaits at the sides 15 and at the center, coat-sleeves and a standing collar being added.

What I claim as my invention, and desire to secure by Letters Patent, is—

The design for a lady's polonaise, as shown in 20 the engraved prints accompanying this specification.

JOHN QUINCY REED.
